THE NORRIS PETERS CO., PHOTO-LITHO., WASHINGTON, D. C.

UNITED STATES PATENT OFFICE.

RICHARD B. CHUTE, JR., OF HUNTINGTON, NEW YORK.

CLAMP.

1,299,822.

Specification of Letters Patent.

Patented Apr. 8, 1919.

Application filed August 13, 1918. Serial No. 249,651.

To all whom it may concern:

Be it known that I, RICHARD B. CHUTE, Jr., a citizen of the United States, and residing at Huntington, L. I., in the county of 5 Suffolk and State of New York, have invented certain new and useful Improvements in Clamps, of which the following is a specification, such as will enable those skilled in the art to which it appertains to make and 10 use the same.

This invention relates to clamps and particularly to devices of this class for use by boat builders in the placement and supporting of boards used in what is known as 15 planking or decking; and the object of the invention is to provide a device of the class specified which is simple in construction and operation and efficient in use, as well as being indestructible in the use thereof; and 20 with this and other objects in view the invention consists in a device of the class and for the purpose specified, constructed and operating as hereinafter described and claimed.

25 The invention is fully disclosed in the following specification, of which the accompanying drawing forms a part, in which the separate parts of my improvement are designated by suitable reference characters in 30 each of the views, and in which:—

Figure 1 is a side view of a part of the hull of a boat and showing one of my improved clamp devices and the method of its use;

35 Fig. 2 a partial section on the line 2—2 of Fig. 1;

Fig. 3 a view looking in the direction of the arrow 3 of Fig. 1 but showing my device detached;

40 Fig. 4 a plan view of the construction shown in Fig. 3; and,

Fig. 5 a face view of a clamp block or clip which I employ.

In Figs. 1 and 2 of the drawing, I have 45 illustrated one use of my improved clamp, and in said figures 10 is one of the vertical ribs or beams which form the skeleton or framework of the hull of a boat or vessel, and at 11 I have shown a part of two of the 50 siding planks or boards secured to the verti-

cal rib 10, and at 12 I have shown my clamp device connected with the rib 10 below the lower plank or board 11.

The clamp 12 consists of an L-shaped body comprising a wide and approximately triangular-shaped front plate 13, and a narrow side plate 14 which forms a guide for the clamp as hereinafter set out. At the top of the front plate 13 is a forwardly directed inclined face plate 15 reinforced by a central 55 web 16, and the face of said plate 15 is provided centrally with an upwardly directed bead 17 which extends the full length thereof, as clearly shown in Figs. 3 and 4.

The front plate 13 is provided with an 60 elongated aperture 18 which is arranged at an angle to the side plate 14, as shown in Fig. 1, and the bottom of said aperture is enlarged at one side as shown at 19. I also employ a clamp block or clip 20 which is of 65 approximately triangular form, and the longer side or face of which is provided with a plurality of teeth or projections 21 as shown in Figs. 1 and 5 of the drawing, and at one side of said clamp block is an outwardly directed lug 22, which is adapted to fit in and operate in the elongated aperture 18, and one face of said lug is provided with a rounded and reduced flange 23 which overlaps one side wall of the aperture 18, as 70 shown in Fig. 1, and locks the clamp block or clip 20 in connection with the front plate 13 but permits of the movement of said clamp block or clip longitudinally of the elongated aperture 18. The outwardly directed lug 22 and flange 23 are adapted to pass through the enlarged portion 19 of the aperture 18, but when said clamp block is connected with the plate 13 a pin 24 is secured in the bottom face of the lug 22 and 75 this pin prevents the displacement of said clamp block from said plate.

The top of the side 14 of the body of the clamp 12 is provided with an upwardly directed portion 25 which is rounded as shown 80 at 26, and the face 27 of the upwardly directed portion is in line with the back face 28 of the front plate 13, as clearly illustrated in Figs. 3 and 4 of the drawing and in the use of the device, or in the placement 85 90 95 100

of and supporting of one of the planks or boards 11, the clamp 12, or the side 14 thereof, is first placed upon one side of the rib 10 with the back face 28 of the front plate 13 upon the face of said rib, as shown in Fig. 2, with the upwardly directed portion 25 at the back of the plank or board 11, after which the clamp is moved vertically to bring the face plate 15 a predetermined distance 10 from the bottom of the plank or board 11, after which the clamp block or clip 20 is moved vertically in the slot to bring the face thereof provided with the teeth or projections 21 in engagement with the opposite 15 sides of the rib 10, as shown in Figs. 1 and 2, after which a wedge 29 is forced between the face plate 15 and the bottom of the plank or board 11 by a hammer or other tool, and this binds the clamp 12 on the rib 10 and 20 moves the plank or board 11 vertically into engagement with the next adjacent plank or board, after which the nails or other attaching devices 30 are passed through said plank or board to secure it to the rib 10.

25 The upwardly directed bead 17 on the face plate 15 is employed to prevent the slipping of the wedge 29 outwardly in the operation of placing the plank or board 11 in position, and it will be understood that while I have 30 shown one use of my improved clamp and certain details of construction for carrying my invention into effect, my invention is not limited to such use of the device, nor to the details of construction herein shown and described, and various changes therein and modifications thereof may be made, within the scope of the appended claims, without departing from the spirit of my invention, or sacrificing its advantages.

35 Having fully described my invention, what I claim as new and desire to secure by Letters Patent, is:—

1. In a clamp of the class described, an L-shaped body one side of which is provided 45 with an elongated aperture, and a clamp block mounted to move longitudinally of said aperture, the top of the clamp being provided with a face plate arranged in an inclined position.

50 2. In a clamp of the class described, an L-shaped body one side of which is provided with an elongated aperture, and a clamp block mounted to move longitudinally of said aperture, the top of the clamp being 55 provided with a face plate arranged in an inclined position, the face of said clamp block being provided with a plurality of teeth.

3. In a clamp of the class described, an 60 L-shaped body one side of which is provided with an elongated aperture ranging at an angle to the other side, the top of said first named side being provided with an inclined face plate, the top of the last named 65 side being provided with an upwardly di-

rected portion, and a clamp block mounted at the back of the first named plate and adapted to operate in said elongated aperture and the face of said clamp block being provided with a plurality of teeth. 70

4. In a clamp of the class described, a front plate of approximately triangular form and a side plate arranged at right angles to said front plate, said front plate being provided with an elongated aperture 75 which ranges at an angle to the side plate and the lower end portion of which is enlarged at one side, the top of the front plate is provided with an outwardly directed face plate ranging in an inclined position, and the face of which is provided with a longitudinal bead or projection, a clamp block the face of which is provided with a plurality of teeth and one side of which is provided with a projecting lug adapted to pass through and operate in the elongated aperture in the front plate, and said lug being provided with a flanged portion which together with the body of said block permit of the sliding of the clamp block longitudinally of the aperture. 80

5. In a clamp of the class described, a front plate of approximately triangular form and a side plate arranged at right angles to said front plate, said front plate 95 being provided with an elongated aperture which ranges at an angle to the side plate and the lower end portion of which is enlarged at one side, the top of the front plate is provided with an outwardly directed face plate ranging in an inclined position, and the face of which is provided with a longitudinal bead, a clamp block the face of which is provided with a plurality of teeth and one side thereof with a projecting lug 100 adapted to pass through and operate in the elongated aperture in the front plate, said lug being provided with a flanged portion which together with the body of said block permit of the sliding of the clamp block longitudinally of the aperture, and means on 105 said lug for preventing the displacement of said clamp block from said front plate. 110

6. In a clamp of the class described, an L-shaped body portion at the top of which is a face plate, one side of the body portion being provided with an elongated aperture arranged at an acute angle to the other side, and a clamp block mounted in and movable longitudinally of said aperture, said block 115 being provided with means for preventing the transverse movement thereof in said aperture. 120

7. In a clamp of the class described, an L-shaped body portion at the top of which is a face plate and one side of the body portion being provided with an elongated aperture, arranged at an angle to the other side, said other side of said body portion being provided at the top thereof with a projection 125 130

which extends above the face plate and the front face of which is in the same plane as the rear face of the first named side of the body portion, and a clamp block mounted in 5 and movable longitudinally of said elongated aperture.

In testimony that I claim the foregoing as

my invention I have signed my name in presence of the subscribing witnesses this 10th day of August, 1918.

RICHARD B. CHUTE, JR.
